UNITED STATES PATENT OFFICE.

KARL FREY, OF ENNETBADEN, SWITZERLAND, ASSIGNOR TO AKTIENGESELLSCHAFT BROWN BOVERI & CIE., OF BADEN, SWITZERLAND, A JOINT-STOCK COMPANY OF SWITZERLAND.

STEAM-TURBINE CONSTRUCTION.

Application filed February 12, 1926, Serial No. 87,740, and in Germany February 14, 1925.

This invention relates to steam turbines and has as its general object the provision of a construction which contributes to facility and economy of manufacture and efficiency of performance.

One of the specific objects is the provision of a construction requiring blades of only one height throughout, on either the rotor or the cylinder or both, or throughout extensive groups of stages. This simplifies and cheapens production, lessens the number of blades which must be made for overage, greatly decreases the number of unlike parts, and from the standpoint of the user, is of great advantage in that it requires his keeping on hand for repair only one or two different types of blades.

Another object is the provision of a construction which gains these advantages with a rotor and cylinder design which is simple and admits of economical manufacture and assembly with facility.

A further object is the provision of a construction in which the aforementioned advantages are secured without sacrifice of efficiency in operation.

Other and further objects and advantages will be pointed out hereinafter, indicated in the claims, or obvious to one skilled in the art upon an understanding of the present disclosures.

In the accompanying drawing forming a part of this specification the nature of a construction embodying the invention is illustrated diagrammatically, it being intended that the invention may take various structural forms, all within the scope of the appended claims.

In the drawing,

Fig. 1 is a graph illustrating in a general way the expansion of steam from stage to stage in a turbine,

Fig. 2 is a diagrammatic illustration in the nature of a part longitudinal section through a part of the casing and rotor of an impulse turbine embodying the invention, and

Fig. 3 is a diagrammatic illustration in the nature of a part longitudinal section through a portion of a turbine of the reaction type in which the invention is embodied.

In turbine construction it is customary to increase the height of the blading from stage

to stage or from one to another of groups of stages of uniform diameter, for the purpose of accommodating the increasing volume of the expanding steam. This necessarily involves the provision of blades of several heights, requiring variety in the treatment of material from which they are cut and multiplication of handling operations, overage requirements, etc. My invention provides a construction wherein blades of uniform height may be used throughout, and high efficiency in operation attained. This I accomplish by progressively increasing the blading diameter in successive stages by such increments as will give the requisite admission area for the steam expanded through the preceding stage of rotor or cylinder blading or cylinder diaphragm and maintain a substantially constant ratio of peripheral speed to steam velocity. The general form of the cylinder is, of course, determined for the most part by the blading diameters.

In Fig. 2 is shown diagrammatically an illustrative structure in which the numeral 10 designates a portion of the rotor shaft and 11 a section of the cylinder or casing. On the rotor discs 12 are carried the rotor blades d_1 , d_2 , d_3 , d_n , and on the stator discs or diaphragms 14 the guide blades c_1 , c_2 , c_3 , c_n . The blades on the several discs 12 are of uniform height and form, as are also those on the several guide discs 14. The blading diameter of the several stages is determined in substantial accordance with the steam volume curve along the blading, shown in Fig. 1. On the graph the volume at the outlets from the blading of the respective guide and rotor stages is indicated by the points a_1 , b_1 , a_2 , b_2 , etc.

The several diameters are so established as to maintain the ratio $\frac{u}{c}$ {peripheral velocity} {steam velocity} substantially uniform for all stages, the admission area in each instance having the same radiae extent, the necessary increase being derived from the increased diameter of the blading and the consequent increase of cross section. The increase in peripheral velocity follows as a function of the increase of diameter. Knowing the volume, the diameters ϕ of the guide and rotor blading may be calculated from the formula $G \cdot v = f \cdot \phi$, wherein G is weight of steam, v is specific volume of steam,

f is annular admission area and c is steam velocity; so, $f = h \cdot \phi \cdot \pi$ and $G \cdot v = h \cdot \phi \cdot \pi \cdot c$. Accordingly, if $\frac{u}{c}$ is to be constant,

5 c will $= k_1 u$ or $k_2 \phi^2$

and with G also a constant,

$$v = k_3 \cdot \phi^2 \text{ or } \phi = k \cdot \sqrt{v}.$$

10 (u is peripheral velocity, h is blade height, k is a constant). In disc turbines the construction may follow the diameter determinations quite closely, and in reaction turbines of the drum construction the determinations may 15 be followed, not with mathematical exactness, but without serious or substantial variation from a uniform ratio of $\frac{u}{c}$ by a structure in which the rotor drum is formed with a conical peripheral surface. Such a construction is illustrated in a general way in Fig. 3, the numeral 12^a designating the conical drum, the characters c_1, c_2, c_3 stator blades, d_1, d_2, d_3 , rotor blades, and 11^a the casing. The blading, on stator and rotor, is of uniform height, and the surfaces of the drum and casing bore are parallel. It will be seen that, in such constructions particularly, the invention contributes greatly to simplification of manufacture and assembly.

30 What I claim is:

1. A multi-stage steam turbine having rotor blades of uniform height and the blading

35 diameter and admission area increasing from stage to stage by amounts maintaining the ratio of peripheral velocity to steam velocity substantially uniform.

2. A multi-stage steam turbine having full admission and the blades of uniform height throughout, the blading diameter increasing 40 from stage to stage by amounts such as to maintain the ratio of peripheral velocity to steam velocity substantially uniform.

3. In a multi-stage steam turbine, a casing 45 having a conical bore surface, a rotor drum having a conical peripheral surface, blades being on said casing and drum of uniform height throughout, and blading diameter increasing from stage to stage in uniform ratio 50 such as to maintain the ratio of peripheral velocity to steam velocity substantially uniform.

4. A turbine construction as specified in 55 claim 3, having the rotor and casing bore surfaces parallel.

5. A multi-stage steam turbine having blades of uniform height in different stages, the blading diameter of the respective stages being such as to maintain the ratio of peripheral velocity to steam velocity substantially 60 uniform for all stages.

In testimony whereof I have hereunto subscribed my name at Zurich, Switzerland on the 20th day of January, A. D. 1926.

KARL FREY.
